UNITED STATES PATENT OFFICE

2,351,968

REFRIGERATOR CONTROL DEVICE

Frederick W. Hottenroth, Jr., Schenectady, N. Y.,
assignor to General Electric Company, a corporation of New York

Application September 5, 1942, Serial No. 457,413

17 Claims. (Cl. 200—83)

My invention relates to refrigerator control apparatus and particularly to temperature responsive refrigerator control switches having manually operable means for temporarily modifying the operation of the switch selectively to effect defrosting or quick-freezing operation thereof. The invention also contemplates automatic disabling of the modifying means after the desired abnormal control operation has been completed.

Accordingly, it is an object of my invention to provide a new and improved refrigerator control switch which is reliable and efficient in operation and simple and inexpensive to manufacture.

It is a further object of my invention to provide a refrigerator control apparatus having push button control means for modifying the normal operation of the switch selectively to effect quick-freezing or defrosting operation at temperatures beyond the normal operating range of the apparatus.

Another object of my invention is to provide a refrigerator control switch having magnetic control means for modifying the normal operation of the switch to effect either quick-freezing or defrosting operation.

It is a still further object of my invention to provide a refrigerator control switch having push button controlled magnetic means for modifying the normal operation of the switch selectively to effect quick-freezing or defrosting operation and arranged automatically to return the switch to its normal mode of operation after the abnormal cycle of operation has been completed.

According to my invention I provide a resiliently mounted switch member arranged for substantially pivotal movement to a contact-closing position by a thermally expansible bellows against the force of a loading spring arranged to maintain following engagement between the bellows and the switch member and to move the switch member to a circuit-opening position upon contraction of the bellows. Preferably the switch member is provided with a snap action by positioning a small permanent magnet adjacent the free end of the switch member in the region of the contacts for cooperation with a magnetizable portion of the switch member which constitutes a keeper for the magnet. To modify the normal cyclic operation of the switch member and to provide an abnormally wide cycle of defrosting operation of the control apparatus I provide manually positionable magnetic means which is normally biased to an ineffective position and ar-

ranged for movement into attractive relation with a magnetic portion of the switch member positively to attract the switch member to its circuit-opening position. The magnetic means applies to the switch member a releasable loading force which aids the loading spring in urging the switch member to its open-circuit position. I also provide magnetic means for modifying the operation of the switch mem-

10 ber in an opposite sense to effect quick-freezing operation of the control apparatus. This latter magnetic means comprises a magnetic member fixedly mounted upon the base of the control apparatus and a manually movable cooperating magnetic member arranged when brought into attractive relation with the fixedly mounted magnetic member to engage the switch member and positively move it to its circuit-closing position. By this latter arrangement a releasable magnetic loading force is applied to the switch member in opposition to the force of the loading spring so that the switch member remains in its circuit-closing position for an abnormally long period.

15 25 30 35 For a more complete understanding of my invention and a further appreciation of its objects and advantages reference should now be had to the following detailed description taken in conjunction with the accompanying drawing in which Fig. 1 is a side elevation of a refrigerator control apparatus embodying my invention showing the device with the casing removed; and Fig. 2 is a sectional view of the apparatus taken along the lines 2—2 of Fig. 1 looking in the direction of the arrows.

40 45 Referring now to the drawing, the control apparatus comprises a switch member 10 resiliently and pivotally mounted at one end upon a base 11 and carrying at its other end a movable contact 12. The base 11 may be formed in any suitable manner, but as shown in the drawings it comprises a U-shaped metallic portion forming a pair of supporting plates 13 and 14 disposed at parallel spaced relation and connected together at one end in combination with a stationary contact block 15 of any suitable insulating material which is positioned between the plates 13 and 14 at their opposite ends.

The switch member 10 comprises an irregularly shaped rigid magnetizable portion 16 which is carried at the free end of a cantilever spring strip 18, the other end of which is attached to a bracket 17 forming part of the base 11. The switch member 10 is controlled by an operating lever 19 which extends in substantially parallel

50 55

relation with the switch member and passes through an aperture 20 in the spring 18 so that opposite ends of the lever 19 extend parallel to the spring 18 and on opposite sides thereof. One end of the lever 19 rests upon the bracket 17 and the other end forms a movable seat for a loading spring 25 which is positioned between the operating lever 19 and the base 11. The spring 25 is a compression spring and exerts a force upon the switch member 10 tending to move the switch member to its circuit-opening position.

For moving the switch member to its circuit-closing position I provide a thermally responsive expansible bellows 26 having one end fixedly mounted upon the upper base plate 13, as by bolts 13a, and a movable end in engagement with an adjustable abutment on the spring 18. Specifically the movable end of the bellows 26 engages the end of a threaded shaft 27 which is adjustably mounted within an internally threaded boss 28 in the operating lever 19 and carries at its other end a gear 29. The interior of the bellows 26 is connected by a flexible tube 30 to a sealed bulb (not shown) which may be mounted in the space the temperature of which is to be controlled. For example, it is well known to those skilled in the art that such a bulb may suitably be mounted upon the evaporator of a refrigerator. The bellows 26, the flexible tube 30 and the attached bulb form a closed space of variable volume which may be filled with any desired thermally expansible fluid. I prefer to utilize a non-volatile fluid so that the entire system is at all times completely filled with a thermally expansible liquid. Since the liquid is substantially incompressible, the position of the movable end of the bellows 26 will then be dependent solely upon the temperature of the expansible fluid in the system and independent of the magnitude of the loading force applied by the compression spring 25.

In order to adjust the normal temperature to be maintained by my control apparatus I provide means for adjusting the spacing between the switch member 10 and the movable end of the expansible bellows 26. As shown in the drawings this adjustment comprises a spur gear 31 mounted upon a shaft 32 which is rotatably journaled in the base 11. The gear 31 meshes with the gear 29 and is arranged for manual rotation from a point exterior of the casing. As shown, the end of the shaft 32 is transversely slotted at 33 and may be turned by any convenient instrument, such as a screw-driver. If desired, the end of the shaft may be provided with a rotatable knob for convenient direct manipulation. Thus, by turning the gear 31 the height of the abutment formed by the end of the threaded shaft 27 may be changed with respect to the internally threaded lug 28 on the operating lever 19 and the spacing between the movable end of the expansible bellows 26 and the switch member 10 may be varied.

The irregular shape of the rigid magnetizable portion 16 of the switch member 10 is best shown at Fig. 2. From this view it will be observed that the contact carrying end of the member 16 is L-shaped and provided with an overhanging contact supporting plate 34 of suitable insulating material. The plate 34 is attached to the member 16 by any suitable means, such as a rivet 35. The movable contact 12 has a stem portion passing through the plate 34, as shown at Fig. 1, and is carried by a small wipe spring 36, the other end

of which is attached to the plate 34, as by riveting at 37. The wipe spring 36 serves also as a current conducting lead and is electrically connected to a line terminal on the insulating base 15 by means of a flexible conductor 38.

For cooperation with the movable contact 12 I provide a fixed contact 39 carried upon a small flat spring 40, one end of which is attached at 41 to the insulating base 15. The contact carrying end of the spring 40 may be adjustably positioned by means of an adjusting bolt 42 mounted in the base 15. To provide the switch member 10 with a snap action there is positioned adjacent the fixed contact 39 a small permanent magnet 45. The magnet 45 is fixedly attached to the base 11 as by a U-shaped strap 46 and is aligned with that portion of the magnetizable member 16 lying adjacent the contact 12. The member 16 serves as a keeper for the permanent magnet 45 and provides the switch member 10 with a snap action in contact engaging and disengaging movements in a manner well known to those skilled in the art.

Since it is frequently desirable in a switch of this type to provide means for manually moving the switch member to an "off" position and positively precluding further control operation of the device until desired, I have shown a push button 47 comprising a head portion exterior of the casing and a slidable plate 48 having a hooked end portion arranged to engage a cooperating hooked end portion 49 formed on the member 16. The plate 48 passes through the base plate 13 and through a parallelly disposed supporting bracket 50 attached to the plate 13. A flexible spring strip 51 attached to the base plate 13 and frictionally engaging the side of the slidable plate 48 serves to hold the plate 48 frictionally in any desired position.

My invention particularly contemplates the provision of manually controllable magnetic means for modifying the normal cyclic operation of the control apparatus to effect quick-freezing or defrosting operation of the apparatus as desired. For this purpose I mount upon the switch member 10 a small permanent magnet 55 which in the drawings is shown attached to the member 16 by a U-shaped clamping strap 56. For cooperation with the magnet 55 to provide defrosting operation of the control apparatus I have shown a small magnetizable keeper 57 which is preferably made of soft iron and is mounted upon the end of a slidable manually operable push button 58. The push button 58 comprises a head portion exterior of the base plate 13 and a stem portion 59 passing through the plate 13 and bracket 50 and having a shoulder 60 positioned therebetween. A compression spring 61 surrounding the stem 59 between the bracket 50 and the shoulder 60 serves to bias the push button 58 to a normal upper limiting position in which the keeper 57 engages the bracket 50 and is spaced from the permanent magnet 55 a sufficient distance to insure that it is beyond the effective attractive range of the magnet. A flat spring 62 attached to the base plate 13 is arranged to be engaged by the shoulder 60 and serve as a resilient lower limit stop for the push button 58.

To provide for temporarily modifying the operation of the switch member 10 for effecting quick-freezing operation of control apparatus I mount a permanent magnet 65 in fixed position upon the base plate 14 by any suitable means, such as a U-shaped clamping strap 66. A movable keeper 67 for cooperation with the magnet 65 is car-

ried by a manually operated push button 58 which is slidably mounted in the base plate 13. The push button 58 comprises a head portion and a shank portion 69 which extends through suitable openings in the base plate 13 and the bracket 50 and carries at its lower end the magnetizable keeper 67. The push button 58 is also similar to the push button 58 in that the shank portion thereof is provided with a shoulder 70 lying between the plate 13 and the bracket 50 and providing an upper seat for a compression spring 71 positioned between the bracket 50 and the shoulder 68 to bias the push button to its outermost position in which the keeper 67 acts as a limiting stop by engagement with the bracket 50. Referring now to Fig. 2 it will be observed that the magnetizable portion 16 of the switch member 10 is cut away at 72 to permit direct engagement of the keeper 67 with the magnet 55. The keeper 67 is provided with a lug 73 arranged to engage the switch member 10 when the keeper moves into attractive relation with respect to the magnet 55. For the purpose of adjusting the position of the switch member 10 with respect to the keeper 67 an adjustable abutment comprising a bolt 74 is arranged on the portion 16 of the switch member 10 for engagement with the lug 73 on the keeper 67. The keeper 67 is normally biased to the position shown at Fig. 1 so that in normal cyclic operation of the switch member 10 the keeper 67 is beyond the range of movement of the switch member and has no effect thereon. Since the magnetizable portion 16 of the switch member 10 is cut away directly above the magnet 55, there is no appreciable influence exerted upon the switch member by the magnet.

From the foregoing detailed description of the various parts of my control apparatus and their relation with respect to each other, it is believed that the operation of the device as a whole will be clear from the following brief description.

To initiate operation of the device from the position shown at Fig. 1 the push button 51 must first be depressed to set free the movable end of the switch member 10. If it is assumed that after this is done the switch member remains in the position shown at Fig. 1 it indicates that the fluid in the temperature responsive bellows 26 is contracted and that the temperature of the controlled space is sufficiently low. If now the temperature of the space to be cooled increases, the bellows 26 will expand and move the switch member 10 into its circuit-closing position against the force of the compression spring 25. In this movement the bellows 26 forces the operating lever 19 to rotate about its point of engagement with the bracket 17 thereby to depress the extending end of the spring strip 18 which carries with it the magnetizable portion 16 of the switch member 10. As the portion 16 of the switch member approaches the snap action magnet 45 the attractive force between the magnet 45 and the switch member gradually increases to a point at which the switch member is suddenly pulled into its circuit-closing position independently of the bellows 26 so that the contacts 12 and 39 engage with a snap action. Closing of the circuit at the contacts 12 and 39 initiates operation of a refrigerating apparatus (not shown) which cools the conditioned space and causes contraction of the fluid in the bellows 26. As the bellows 26 contracts the operating lever 19 is held in following engagement with the movable end of the bellows by the compression spring 25 so that the operating lever is grad-

ually moved upwardly to bias the cantilever spring 18 to a circuit-opening position. When the stress of the spring 18 attains a predetermined value, it will be sufficient to overcome the force of the snap action magnet 45 and the magnet 45 will release the switch member 10 to permit it to move to its circuit-opening position with a snap action. It will be understood that the foregoing opening and closing movement of the switch member 10 continues in a cyclic manner to maintain the temperature of the space to be cooled within the limits of a predetermined normal range. The limits of this predetermined normal range may be adjusted by manipulation of the shaft 30 to adjust the spacing between the operating lever 19 and the movable end of the bellows 26.

If it is desired to obtain defrosting operation of the control apparatus the push button 58 is depressed until the keeper 67 engages the permanent magnet 55. If this operation is carried out with the switch member 10 in its open-circuit position the shoulder 60 of the push button 58 will be brought into engagement with the stop spring 62 which resiliently resists further downward movement of the push button 58 and its keeper 67. If the switch member 10 is in its circuit-closing position when the push button 58 is depressed, the shoulder 60 deforms the spring 62 as the push button is manually moved until it engages the magnet 55, and upon release of the push button the spring 62 returns to substantially its normal shape and in so doing it partially returns the push button 58 and positively moves the switch member 10 to its circuit-opening position. When the keeper 67 is in engagement with the magnet 55 there is applied to the switch member a releasable magnetic loading force which aids the loading spring 25 in resisting circuit-closing movements of the switch member 10. The switch member will now fail to close the contacts 12 and 39 when the temperature of the conditioned space reaches the upper limit of its normal range because, although due to the incompressibility of the liquid in the bellows 26 the operating lever 19 has been depressed to its circuit-closing position, the magnetic attraction between the magnet 55 and its keeper 67 deforms the cantilever spring 18 and prevents circuit-closing movement of the magnetizable portion 16 of the switch member. Consequently, the temperature of the conditioned space continues to rise so that the operating lever is further depressed and the spring 18 is further deformed. When the deformation of the spring 18 reaches a predetermined point its bias will be sufficient to overcome the attractive force between the magnet 55 and its keeper 67 so that the portion 16 of the switch member 10 will be released with a snap action and will move quickly to its circuit-closing position in which it is attracted by the snap action magnet 45. As soon as the keeper 67 releases the magnet 55 the compression spring 61 returns the push button 58 to its normal inactive position shown at Fig. 1. The spring 61, therefore, effects automatic disabling of the defrosting adjustment as soon as a single defrosting cycle has been completed. It will be understood that while such a spring is desirable it is also possible to provide apparatus in which the push button 58 remains in its depressed position after it releases the magnet 55, so that upon return of the switch member 10 to its circuit-opening position attraction between the magnet 55 and its keeper 67 will be reestablished.

and another defrosting cycle will be initiated. In such a case discontinuance of the defrosting operation could be accomplished only by manual withdrawal of the push button 68.

If now it is desired to effect quick-freezing operation of the control apparatus the push button 68 may be depressed until the keeper 67 engages its cooperating permanent magnet 65. If this operation is carried when the switch member 10 is in its closed-circuit position the lug 73 will simply be brought into the path of movement of the abutment 74. If, on the other hand, the push button 68 is depressed when the switch member 10 is in its circuit-opening position the lug 73 will engage the abutment 74 and positively carry the portion 16 of the switch member 10 to its circuit-closing position. It will be evident that the attractive force between the permanent magnet 65 and its keeper 67 applies to the portion 16 of the switch member 10 a magnetic loading force opposing the force of the loading spring 25 and aiding the snap action magnet 45. Thus, when the temperature of the space to be cooled reaches the lower limit of its normal range the operating lever 19 will be in its normal circuit-opening position due to the incompressibility of the liquid in the bellows 26, but the portion 16 of the switch member 10 will be retained in its circuit-closing position against the bias of the cantilever spring 18 due to the force of attraction between the magnet 65 and its keeper 67. As the temperature of the conditioned space decreases below the lower limit of its normal range the bellows 26 further collapses and the operating lever 19 is further rotated in a clockwise direction as viewed in the drawing so that the cantilever spring 18 is additionally stressed. When the stress of the spring 18 reaches a predetermined point it will be sufficient to overcome the force of attraction of the magnet 65 for its keeper 67 and the magnet 45 for the member 16 so that the portion 16 of the switch member 10 will move upwardly and will force the keeper 67 out of engagement with the magnet 65. As soon as the keeper 67 is released by the magnet the compression spring 71 will move the push button 68 and its attached keeper 67 to the normal position shown at Fig. 1, thereby to release the switch member 10 and permit it to move with a snap action to its circuit-opening position shown in the drawing.

While I have shown only a single embodiment of my invention by way of illustration many further modifications will occur to those in the art. I therefore wish to have it understood that by the appended claims I wish to cover all such modifications as fall within the true spirit and scope of my invention.

What I claim as new and desired to secure by Letters Patent of the United States is:

1. In a refrigerator control apparatus for controlling the temperature of a space to be cooled, a switch member movable between circuit-opening and circuit-closing positions to control said temperature, expansible means responsive to said temperature for effecting cyclic operation of said switch member between said positions normally to maintain said temperature within a predetermined range, a pair of permanent magnets operatively associated with said switch member, a first magnetizable member normally spaced from one of said magnets and movable into attractive relation therewith releasably to bias said switch member to a circuit-opening position thereby temporarily to maintain said space at a temper- 75

ature above said predetermined range, and a second magnetizable member normally spaced from the other of said magnets and movable into attractive relation therewith releasably to bias said switch member to a circuit-closing position thereby temporarily to maintain said space at a temperature below said predetermined range.

2. In a refrigerator control apparatus for controlling the temperature of a space to be cooled, 10 a switch member movable between circuit-opening and circuit-closing positions to control said temperature, expansible means responsive to said temperature for effecting cyclic operation of said switch member between said positions normally to maintain said temperature within a predetermined range, a permanent magnet operatively associated with said switch member, and a magnetizable member biased to a position normally spaced from said magnet and movable into attractive relation therewith releasably to retain said switch member in a circuit-opening position thereby temporarily to maintain said space at a temperature above said predetermined range.

3. In a refrigerator control apparatus for controlling the temperature of a space to be cooled, 25 a switch member movable between circuit-opening and circuit-closing positions to control said temperature, expansible means responsive to the temperature of said space for effecting cyclic operation of said switch member between said positions normally to maintain said temperature within a predetermined range, a permanent magnet operatively associated with said switch member, and a magnetizable member biased to a position normally spaced from said magnet and movable into attractive relation therewith releasably to retain said switch member in a circuit-closing position thereby temporarily to maintain said space at a temperature below said 40 predetermined range.

4. In a refrigerator control apparatus for controlling the temperature of a space to be cooled, 45 a pivoted switch member movable between circuit-opening and circuit-closing positions to control said temperature, said switch member including a magnetic portion, means for biasing said switch member to said circuit-opening position, an expansible bellows having a portion movable in response to said temperature to move said switch member to said circuit-closing position thereby to effect cyclic operation of said switch member normally to maintain said temperature within a predetermined range, magnetic means mounted for limited movement and normally positioned in spaced relation to said magnetic portion of said switch member, said magnetic means being movable into attractive relation with said magnetic portion of said switch member thereby releasably to retain said switch member in one of said circuit-controlling positions for an abnormal period so that said space temporarily assumes a temperature beyond said predetermined range.

5. In a refrigerator control apparatus for controlling the temperature of a space to be cooled, 65 a base, a switch member pivotally mounted upon said base and movable between circuit-opening and circuit-closing positions to control said temperature, means for biasing said switch member to said circuit-opening position, an expansible bellows having a portion movable in response to said temperature to move said switch member to said circuit-closing position thereby to effect cyclic operation of said switch member and normally to maintain said temperature within a pre-

determined range, a first magnetic member fixedly mounted upon said base in spaced relation to said switch member, and a second magnetic member normally spaced from said first magnetic member and movable into attractive relation therewith, said second magnetic member being arranged to engage said switch member when moved into attractive relation with said first magnetic member and releasably to retain said switch member in one of said circuit-controlling positions for an abnormal period so that said space temporarily assumes a temperature beyond said predetermined range.

6. In a refrigerator control apparatus for controlling the temperature of a space to be cooled, a base, a switch member pivotally mounted upon said base for movement between circuit-opening and circuit-closing positions, a spring for biasing said switch member to said circuit-opening position, a fluid filled bellows expandible and contractible in response to the temperature of said space to move said switch member to said circuit-closing position in opposition to the bias of said spring thereby normally to maintain said temperature within a predetermined normal range, a permanent magnet mounted upon said switch member, a magnetizable keeper operatively associated with said permanent magnet, said keeper being normally positioned beyond the effective attractive range of said permanent magnet, and manual means for moving said keeper to a second position in attractive relation with said permanent magnet thereby to apply to said switch member an abnormal biasing force toward one of its circuit-controlling positions so that said space temporarily assumes a temperature beyond said normal range.

7. In a refrigerator control apparatus for controlling the temperature of a space to be cooled, a base, a switch member pivotally mounted upon said base and movable between circuit-opening and circuit-closing positions to control said temperature, means for biasing said switch member to said circuit-opening position, an expandible bellows having a portion movable in response to said temperature to move said switch member to said circuit-closing position thereby to effect cyclic operation of said switch member and normally to maintain said temperature within a predetermined range, a permanent magnet fixedly mounted upon said base, a movable keeper for said magnet normally spaced from said magnet and having a portion positioned to engage said switch member positively to move said switch member to one of its circuit-controlling positions, and means for moving said keeper into attractive relation with said magnet thereby to apply to said switch member a magnetic loading force for releasably retaining said switch member in said one position for an abnormal period, whereby said space temporarily assumes a temperature beyond said predetermined range.

8. A refrigerator control device comprising a switch member movable between circuit-opening and circuit-closing positions, magnetic means arranged to provide movement of said switch member between said positions with a snap action, temperature responsive means for moving said switch member to said circuit-closing position, a loading spring engaging said switch member to oppose said temperature responsive means and to bias said switch member to said circuit-opening position, a permanent magnet mounted upon said switch member, a movable keeper for said permanent magnet biased to a normal position

beyond the effective attractive range of said magnet, and a manually operable push button for moving said keeper into attractive relation with said magnet, said keeper being arranged to attract said switch member to said circuit-opening position and releasably to oppose movement of said switch member to said circuit-closing position thereby to effect a condition of defrosting operation of said control device.

10 9. A refrigerator control device comprising a switch member movable between circuit-opening and circuit-closing positions, magnetic means arranged to provide movement of said switch member between said positions with a snap action, temperature responsive means for moving said switch member to said circuit-closing position, a loading spring engaging said switch member to oppose said temperature responsive means and to bias said switch member to said circuit-opening position, a permanent magnet mounted upon said base, a movable keeper operable in conjunction with said permanent magnet and biased to a normal position beyond the effective attractive range of said magnet, a manually operable push button for moving said keeper into attractive engagement with said magnet, and a lug carried by said keeper and arranged for movement into the path of movement of said switch member positively to move said switch member to said circuit-closing position, whereby the attractive force between said magnet and said keeper releasably opposes movement of said switch member to said circuit-opening position to effect a condition of quick-freezing operation of said control device.

35 10. A refrigerator control device comprising a space, a magnetic switch member movable between circuit-opening and circuit-closing positions, a magnetic means mounted upon said base and operable in conjunction with said switch member to provide said switch member with a snap action, temperature responsive means for moving said switch member to said circuit-closing position, a loading spring engaging said switch member to oppose said temperature responsive means and to bias said switch member to said circuit-opening position, first movable magnetic means biased to a normal position spaced from said magnetic switch member, a manually operable push button for moving said movable magnetic means into attractive relation with said switch member, said movable magnetic means being arranged to attract said switch member to said circuit-opening position and releasably to oppose movement of said switch member to said circuit-closing position thereby to effect a condition of defrosting operation of said control device, a fixed magnetic member mounted upon said base in spaced relation to said switch member, and second movable magnetic means operable in conjunction with said fixed magnetic member and biased to a normal position beyond the effective attractive range of said member, a second manually operable push button for moving said second movable magnetic means into attractive engagement with said fixed magnetic member, and a lug movable with said second movable magnetic means into the path of movement of said switch member, said keeper and lug being arranged positively to move said switch member to said circuit-closing position and releasably to oppose movement of said switch member to said circuit-opening position thereby to effect a condition of quick-freezing operation of said control device.

11. A refrigerator control device comprising a switch member movable between circuit-opening and circuit-closing positions, a thermally responsive expandible bellows for moving said switch member to said circuit-closing position, a loading spring engaging said switch member to oppose said expandible bellows and to move said switch member to said circuit-opening position, magnetic means manually movable into engagement with said switch member positively to move said switch member to said circuit-closing position and releasably to oppose said loading spring thereby to effect quick-freezing operation of said control device, and second magnetic means manually movable into engagement with said switch member positively to move said switch member to said circuit-opening position and releasably to oppose said expandible bellows thereby to effect defrosting operation of said control device.

12. A refrigerator control device comprising a base, a switch member mounted upon said base for movement between circuit-opening and circuit-closing positions, a thermally expandible bellows for moving said switch member to said circuit-closing position, a loading spring engaging said switch member to oppose said thermally expandible bellows and to move said switch member to said circuit-opening position, manually adjustable means for varying the bias upon said loading spring thereby to select a normal operating range for said control device, magnetic means mounted upon switch member, a first manually movable magnetic member normally biased to a position spaced from said magnetic means and movable into attractive engagement therewith to bias said switch member to said circuit-opening position and releasably to aid said loading spring thereby to effect defrosting operation of said control device, magnetic means mounted upon said base, and a second manually movable magnetic member normally biased to a position beyond the effective range of second magnetic means and movable into attractive engagement therewith, said second movable magnetic member being provided with means engaging said movable switch member positively to move said switch member to said circuit-closing position and releasably to oppose said loading spring thereby to effect quick-freezing operation of said control device.

13. A refrigerator control apparatus comprising a base, a switch member mounted for movement between circuit-opening and circuit-closing positions, said switch member comprising a cantilever spring attached at one end to said base and carrying at its other end a rigid magnetizable member, a liquid-filled thermally expandible bellows engaging said spring intermediate its ends to move said switch member to said circuit-closing position, a loading spring for maintaining following engagement between said switch member and said bellows and moving said switch member to its circuit-opening position thereby to effect cyclic operation of said switch member in response to temperatures within a predetermined normal range, and magnetic means movable into engagement with said rigid magnetizable portion of said switch member and arranged to apply to said switch member a releasable magnetic loading force thereby temporarily to maintain a temperature beyond said predetermined normal range.

14. A refrigerator control apparatus comprising a base, a switch member mounted for movement between circuit-closing and circuit-open-

ing positions, said switch member comprising a cantilever spring attached at one end to said base and carrying at its other end a rigid magnetizable member, a liquid-filled thermally expandible bellows engaging said spring intermediate its ends to move said switch member to said circuit-closing position, a loading spring for maintaining following engagement between said switch member and said bellows and moving said switch member to said circuit-opening position thereby to effect cyclic operation of said switch member in response to temperatures within a predetermined normal range, an adjustable abutment on said switch member for varying the relation of said switch member to said bellows thereby to adjust the limits of said normal range, and magnetic means normally biased to an ineffective position and manually movable into engagement with said magnetizable portion of said switch member to apply to said portion a releasable magnetic loading force thereby temporarily to maintain a temperature beyond said normal range.

15. A refrigerator control apparatus comprising a base, a switch member mounted for movement between circuit-opening and circuit-closing positions, said switch member comprising a rigid magnetizable portion attached at one end of said base by a cantilever spring, a snap action magnet operable in conjunction with said rigid magnetizable portion of said switch member, an adjustable abutment mounted upon said cantilever spring intermediate its ends, a liquid-filled temperature responsive expandible bellows engaging said abutment to move said switch member to said circuit-closing position, a loading spring for maintaining following engagement between said adjustable abutment and said bellows and moving said switch member to said circuit-opening position thereby to provide cyclic operation of said switch member in response to temperatures within a predetermined normal range, manually operable means for adjusting the position of said abutment to vary the spacing between said abutment and said bellows thereby to select upper and lower limits of said normal range, a pair of permanent magnets operatively associated with said switch member, a first magnetizable member biased to a normal position spaced from one of said magnets and movable into attractive relation therewith releasably to bias said rigid portion of said switch member to a circuit-opening position and thereby temporarily to maintain a temperature above said normal range, and a second magnetizable member biased to a normal position spaced from the other of said magnets and movable into attractive relation therewith releasably to bias said switch member to a circuit-closing position and thereby temporarily to maintain a temperature below said predetermined normal range.

16. A refrigerator control apparatus comprising a base, a switch member mounted upon said base for movement between circuit-opening and circuit-closing positions, said switch member comprising a rigid magnetizable portion and a cantilever spring pivotally connecting said rigid portion to said base, a liquid-filled expandible bellows engaging said cantilever spring intermediate its ends to move said switch member to said circuit-closing position, a loading spring for maintaining following engagement between said bellows and said spring and moving said switch member to said circuit-opening position thereby to effect cyclic operation of said switch member

in response to temperatures within a predetermined normal range, and magnetic means manually positionable to engage said rigid portion of said switch member in one of its circuit-controlling positions, said magnetic means applying to said rigid portion of said switch member a releasable loading force producing deformation of said cantilever spring prior to movement of said switch member to the other of said circuit-controlling positions while said bellows moves beyond its normal limits of movement, whereby said temperature is permitted temporarily to assume a value without said predetermined range.

17. In a refrigerator control apparatus for controlling the temperature of the space to be cooled, a switch member movable between circuit-opening and circuit-closing positions to control said temperature, means responsive to said temper-

ature for effecting cyclic operation of said switch member between said positions normally to maintain said temperature within a predetermined range, a pair of magnetic members including a permanent magnet operatively associated with said switch member, one of said magnetic members being mounted upon said switch member and the other of said magnetic members being movably mounted with respect thereto and normally biased to a position out of attractive relation with said one member, said movably mounted magnetic member being movable into attractive relation with said one magnetic member releasably to retain said switch member in a predetermined circuit controlling position thereby temporarily to maintain said space at a temperature beyond said predetermined range.
